UNITED STATES PATENT OFFICE.

MAXWELL GERSON DUMAS, OF PITTSBURGH, PENNSYLVANIA, ASSIGNOR TO DUMAS ENGINEERING COMPANY, OF YOUNGSTOWN, OHIO, A CORPORATION OF OHIO.

HOT TOP FOR INGOT MOLDS.

Continuation of application Serial No. 221,461, filed September 23, 1927. This application filed July 27, 1928. Serial No. 295,680.

This invention relates to hot tops for ingot molds and is a continuation of application Serial Number 221,461, filed September 23, 1927, for hot top for ingot molds.

During the casting of steel and other ferrous alloy ingots, it is customary to pour the molten metal into a mold. Cooling in the mold takes place from the sides and bottom of the ingot, resulting in the formation of a cavity or pipe in the upper central portion of the ingot. A large portion of impurities present in the ingot are forced into the cavity or pipe.

Before the ingot can be subjected to its final finishing operation, it is necessary to cut off or crop the upper defective portion of the ingot, with a resulting waste of material. In order to reduce the losses incident to the cropping of ingots, hot tops or sink heads have been provided to serve as reservoirs of molten metal for filling the cavity formed during the solidification of the ingots. The walls of such hot tops are heat insulated in order to insure that the metal contained therein remains in a liquid state until after the solidification of the metal in the ingot.

Heretofore, such hot tops have had substantially straight side walls. Experience has shown that in a hot top having a straight side wall, solidification takes place uniformly inwardly from the side walls, with the result that a shell of solidified metal surrounds the liquid metal preserving it in its liquid state for filling the cavity in the ingot. The thickness of such a protecting shell depends upon the size of the ingot and the rate of heat dissipation from the hot top. With a straight side hot top, the solidified metal, after the cooling operation of the ingot and metal in the hot top is completed, assumes the general shape of a block with substantially parallel sides. In such a structure the openings for permitting movement of molten metal from the hot top to the ingot proper during the final stages of solidification, has been materially greater than necessary, resulting in the formation and wastage of a large block of metal as cropage.

I have found that by narrowing the sides of the hot top adjacent to the top of the mold, a material saving in the amount of

cropage is obtained. I also propose to narrow the upper portion of the hot top in order to eliminate the upper corners of cropage blocks as heretofore made. By inwardly drawing the portions of the wall of the hot top, I reduce the total radiating surface of the hot top as well as reduce the amount of material "frozen" therein without sacrificing any efficiency in its operation.

The narrowing of the side walls of the hot top to form a constricted opening at the top and a constricted neck portion at the bottom for the purpose stated is made possible by the increased efficiency in retaining the heat of the molten metal which is afforded by a structure of this form which serves to materially reduce the radiation losses inherent in straight wall hot top structures.

With a structure embodying my invention I am able to increase the height of the hot top and thereby the pressure of the molten metal forced into the ingot cavity by substantially 14%, and at the same time reduce the volume of the cropage by 25 to 30%. In a structure with a straight sided hot top, the cropage is substantially 15% of the total metal poured into the mold. With my structure the cropage is only about 8% of the total metal poured. With a 20 inch mold the amount of cropage with a straight side hot top is frequently in the neighborhood of twelve hundred (1200) pounds. Accordingly, the monetary value of the cropage, the value of which is several cents a pound, constitutes a considerable item in the cost of the finished ingots. Accordingly, by utilizing a hot top embodying my invention I am able to effect a material reduction in the cost of molding ingots.

I prefer to use a ceramic material for the hot top in order to secure heat insulation.

By mixing the ceramic material with clay and particles of wood or other combustible substances before the ceramic material is fired, I am able to produce a porous hot top. The pores resulting from the combustion of the material during the burning of the ceramic mass, are filled with air which serves as a good heat insulator. The inner face of the hot top is painted with a refractory slip of clay and water before the hot top is fired. The resulting refractory lining for the hot

top prevents the circulation of the air entrapped in the pores and prevents the molten metal from eating into such pores.

While I have described the use of pores 5 in the hot top, it is to be understood that the hot top may be made without such pores.

A suitable cap is provided for closing the upper end of the hot top. The cap is made more porous than the body of the hot top, 10 and is not provided with a refractory lining in order to permit the escape of gases.

The accompanying drawings illustrate the present preferred embodiment of the invention, in which:

15 Figure 1 is an elevational view of a mold and hot top.

Figure 2 is a plan view thereof.

Figure 3 is a sectional view of a hot top embodying my invention, and

20 Fig. 4 is a perspective view of a cap.

Referring to Figure 1, an ingot mold 1, of any desired cross sectional shape is provided with a hot top 2 having a mid-section 4 of greater diameter than its upper and 25 lower sections 5 and 6 respectively, whereby the chamber defined within it approaches a sphere in shape. The outer walls of the hot top may be straight or tapered as the case may be, although it is preferably 30 formed as illustrated for economy in the use of material.

The hot top is provided with an upper opening 7 and a lower opening 8. The opening 8 is, in part, defined by a flange 9 35 that extends downwardly into the body of the mold 1. The horizontal cross sectional shape of the flange 9 may be varied in accordance with the shape of the mold 1 with which it is associated. A variety of shapes 40 such as rectangular or other polygonal shapes are on the market. A shoulder 10 is provided above the flange 9 for engaging the upper surface of the mold 1 and supporting the hot top. A cap 11 is provided for 45 closing the opening 7.

The material of the hot top 2 is preferably ceramic material made porous by inserting small particles of combustible material in the ceramic material before it is 50 fired. A suitable ceramic material is refractory clay, which when fired produces a body of refractory material having a melting or slagging temperature considerably in excess of the temperature of molten steel. 55 If desired the combustible material may be omitted from the ceramic material before the firing operation, in which case pores 14 will not be formed in the refractory material.

60 The inner surface of the hot top 2 is provided with a refractory lining 12 produced by painting the inner surface of the hot top by a slip of clay, which when fired produces a smooth surface that closes the pores 65 and prevents the circulation of air between

the pores and also prevents the molten metal from eating into the pores 14. The material of the cap 11 is preferably of very porous ceramic material and is not lined in order to permit the escape of gases confined above 70 the top of the molten metal.

I have found that by making the ratio of the diameters of the opening 8 at least one-fourth of that of the portion 4 of the hot top, satisfactory results may be obtained. 75 At the same time, the saving of wasted metal by reducing the diameters of the sections 5 and 6 of the hot top is considerable as has been previously described.

By tapering the walls of the hot top inwardly from the mid-section 4, I reduce the radiating surface of the hot top and thereby secure a greater conservation of heat. The height of the hot top constructed with tapering upper and lower sections 5 and 6, respectively, may be increased by approximately 15% over a straight sided hot top and at the same time produce a saving of 25% in the metal in the hot top. By increasing the height of the hot top, the 90 pressure of the molten liquid applied to the center of the ingot is increased, thereby insuring greater soundness in the upper portion of the ingot.

While I have illustrated and described the 95 preferred embodiment of the invention, it is to be understood that various changes may be made therein without departing from the spirit of the invention or the scope of the appended claims.

I claim:

1. A hot top or sink head having its interior mid portion of greater diameter than the upper and lower portions.

2. In a hot top or sink head, a hollow body having a predetermined inner dimension at its intermediate section, the body tapering inwardly in both directions from the intermediate section, and terminating in openings at the upper and lower ends thereof.

3. In a hot top, a hollow body having a lower opening and an intermediate portion of greater dimension than said opening, the diameter of the lower opening being at least one-fourth of that of the intermediate portion.

4. In a hot top structure a hollow body portion the interior of which is of substantially spherical form and having openings in vertical alignment.

5. In a hot top a hollow body having its interior mid portion of greater diameter than its upper and lower portions and having a restricted portion intermediate the mid portion and the lower portion.

In testimony whereof I have hereunto set my hand this 24 day of July, 1928, at Pittsburgh, Pa.

MAXWELL GERSON DUMAS.
